[57] CLAIM

The ornamental design for a stuffed animal figure and pillow, as shown and described.

DESCRIPTION

FIG. 1 is a perspective view of a stuffed animal figure and pillow showing my new design;
FIG. 2 is an elevational view of the left side, the right
elevational view being a mirror image thereof;
FIG. 3 is a top plan view;
FIG. 4 is a front elevational view; and
FIG. 5 is a rear elevational view.
